US0D1112747S

(12) **United States Design Patent** (10) Patent No.: **US D1,112,747 S**
(45) Date of Patent: ** Feb. 10, 2026

(54) **DENTAL IMPLANT**

(71) Applicant: **OSSTEM IMPLANT CO., LTD.**,
Seoul (KR)

(72) Inventors: **Dong Chan Kim**, Seoul (KR); **Hyun Soo Park**, Gimpo-si (KR)

(73) Assignee: **OSSTEM IMPLANT CO., LTD.**,
Seoul (KR)

(**) Term: **15 Years**

(21) Appl. No.: **35/521,918**

(22) Filed: **Apr. 3, 2024**

(80) **Hague Agreement Data**

Int. Filing Date: **Apr. 3, 2024**

Int. Reg. No.: **DM/238924**

Int. Reg. Date: **Apr. 3, 2024**

Int. Reg. Pub. Date: **Aug. 9, 2024**

(30) **Foreign Application Priority Data**

Oct. 6, 2023 (KR) 30-2023-0039326

(57) **CLAIM**

The ornamental design for a dental implant as shown and described.

DESCRIPTION

1. Dental implant

Description of the Reproduction(s):

1.1 is a perspective view of a dental implant;

1.2 is a front view thereof;

1.3 is a back view thereof;

1.4 is a left side view thereof;

1.5 is a right side view thereof;

1.6 is a top view thereof;

1.7 is a bottom view thereof;

1.8 is a cross sectional view sectioned vertically at the center of 1.2.

The broken lines shown in the figures depict portions of the dental implant that form no part of the claimed design.

1 Claim, 8 Drawing Sheets
